CLAIM

The ornamental design for a pet carrier, as shown and described.

DESCRIPTION

FIG. 1 is an upper perspective view of a pet carrier showing the new design;

FIG. 2 is a lower perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof;

FIG. 8 is a bottom view thereof;

FIG. 9 is a lower perspective view thereof showing placement of optional casters; and,

FIG. 10 is a bottom view thereof without the optional casters.

The portions shown in broken lines are not part of the claimed design.

1 Claim, 10 Drawing Sheets
